UNITED STATES PATENT OFFICE.

STEPHEN S. NEWTON, OF BROOKLYN, NEW YORK.

DESIGN FOR A MEDAL.

SPECIFICATION forming part of Design No. 17,009, dated November 30, 1886.

Application filed October 7, 1886. Serial No. 215,638. Term of patent 14 years.

To all whom it may concern:

Be it known that I, STEPHEN S. NEWTON, a citizen of the United States, residing at Brooklyn, in the county of Kings and State of New York, have invented a certain new and useful Design for a Medal, of which the following is a specification, reference being had therein to the accompanying drawings.

Figure 1 is a view of the obverse of my design for a medal, somewhat enlarged. Fig. 2 is a view of the reverse, similarly enlarged.

Upon the obverse there is an ornamental border of a bead or raised edge, A, which is quite narrow, and an interior concentric circle of either raised points or depressions B B at short distances from each other, this circle of points or depressions being of somewhat less diameter than the rib or bead A. Within this circle or ornamental border there is a substantial fac-simile of a statue with uplifted arm C, torch D, the points or rays E about the head, and the book or tablet supported by the left arm. The statue is mounted upon the pedestal F, which bears a very close resemblance to the pedestal of the statue on Bedloe's Island in New York Harbor. Below and surrounding the pedestal and lower part of the statue is a representation of the adjacent portion of New York Harbor and the lower end or portion of the city of New York, the view of these parts being taken from a point below the statue looking north. On the upper part of this obverse, and in the form of nearly a semicircle, is a row of stars, G, and a

panel adapted to receive a suitable inscription. 35 There is a corresponding panel below the base of the pedestal. On the reverse of the medal (shown in Fig. 2) there is a similar beaded edge, A, and row of points or depressions B, as an ornamentation. In the central part of 40 this reverse there is an oval panel, H, with a representation of a man's head, between which and the ornamental border is a representation of olive-branches.

What I claim as new is—

1. A design for a medal having a representation of the statue "Liberty Enlightening the World" mounted on a pedestal surrounded by an ornamental border, with a panel above the pedestal adapted to receive a suitable inscription and a panel below the pedestal adapted to receive a suitable inscription, substantially as shown.

2. A design for a medal having a central oval panel with the representation of a human head surrounded by an ornamental border, with olive-branches below the panel and a space on either side of the panel adapted to receive a suitable inscription, outside of which is a circle of raised points or depressions and 50 a beaded edge, substantially as shown.

In testimony whereof I affix my signature in presence of two witnesses.

STEPHEN S. NEWTON.
